UNITED STATES PATENT OFFICE.

WILHELM RABUS, OF KARLSTAD, SWEDEN, ASSIGNOR TO ROBERT J. MARX, OF LONDON, ENGLAND.

BEATING ENGINE.

Application filed July 17, 1914. Serial No. 851,576.

To all whom it may concern:

Be it known that I, WILHELM RABUS, a subject of the German Emperor, residing at Karlstad, Sweden, Mariedelsgatan 17, 5 have invented new and useful Improvements in or Relating to Beating Engines, of which the following is a specification.

This invention relates to beating engines or Hollanders of that type in which the 10 beater roll is mounted in a casing at one end of an inclined trough or course of uniform gradient through which the stuff is caused to travel so that the pulp is caused to change its position in the trough after each complete 15 circuit. Hitherto these machines as a rule consisted of an oblong or oval trough divided by a partition into two channels or passages. This method of construction had the drawback that more particularly at the 20 merging point between the two passages formed by the central partition accelerations and retardations of the stuff took place owing to the reversal of the direction of flow of the pulp whereby also the circulation in 25 the engine was reduced and became irregular.

Such drawbacks are obviated and material improvements are obtained by the present invention. The course or channel of my 30 new beater through which the stuff is circulated has a uniform fall or gradient from beginning to end. It has a spiral form or substantially so and in cross-section is substantially U-shaped in that its bottom is 35 dished and its walls straight. The spiral channel forms a uniformly curved path for the stuff, giving the stuff a uniflow direction of travel uninterrupted by obstructions and therefore, its flow is eddyless. The movement of the stuff is thereby made uniform 40 throughout the whole cross section of the dished portion of the channel from the point where it issues from the beater roll to that where it re-enters the roll. In this manner 45 it becomes possible to treat stuff of greater density than hitherto and to considerably increase the speed of circulation.

The invention is illustrated by way of example in the accompanying drawings, in 50 which:

Fig. 1 is a lateral view and Fig. 2 a plan view of a beating engine constructed according to this invention.

Fig. 3 shows on a slightly reduced scale the channel developed in longitudinal section. 55

In the constructional form of the machine shown the beater roll *i* rotates in a box-shaped extension *g* of the channel *a*. Whereas hitherto the channel was as a rule contained in an oblong or oval shaped enclosure according to this invention the channel *a* 60 has a spiral form as shown more particularly in Fig. 2. A vertical central partition *c* which is suitably curved so that it forms a substantially annular midfeather, divides the course of flow into two parts *d* and *f* of approximately semi-circular spiral shape through which the stuff is caused constantly to circulate. By the spiral shape of the 65 channel an entirely uniform circulation is attained since the stuff follows a continuously curved path free from any obstruction in contra-distinction to the action which takes place in ordinary troughs in which at 70 the merging point between the passages *d* and *f* alternating accelerations and retardations of the pulp can not be avoided. 75

In order to further increase the uniformity and rapidity of circulation, the channel 80 is given a uniform gradient along its whole annular extent as shown in Fig. 3. The gradient extends from the point at which the stuff enters the spiral channel on leaving the beater roll *i* almost down to the 85 point at which it re-enters the roll whereby the speed of circulation in the engine is increased, so as to permit efficient treatment of the stuff at greater densities.

In order to ensure a thorough mixing 90 of the stuff, the spiral channel as shown more particularly in Fig. 2 is provided immediately in front of the beater roll where the stuff is discharged into the channel by a short partition *h* which divides the beginning of the channel into two streams. The result of this arrangement is that the stream of stuff which has travelled round the outer line of the channel, on its return 95 to the beater roll is discharged into the 100 passage *l* and thereby is constructed against the inner line *c*. The shape given to the latter and the influence of the partition *h* direct this stream outwardly across the width of the channel, causing it to be 105 thoroughly mixed with the stream of stuff

which during its previous circuit has travelled along the inner line of the channel and which issues from the passage *m*.

- The stuff delivered from the roll is more of a mass than a fluid and therefore its flow or more properly, its bodily movement along the channel for conveying it from the top of the roll to or adjacent to the bottom of the roll, must be facilitated or accelerated as much as possible. To that end, I desire to use the weight and pressure of the stuff delivered from the roll to accelerate or urge or impel the stuff along and that a minimum of friction may be produced in the passage of the stuff through the channel, the stuff to pass through a single continuous spiral channel having a uniform incline or gradient and whose width progressively increases.
- That the acceleration or "urge" of the stock may be effectively produced, I curve or so shape the partition *b* and the similar part of the partition *c* that either of them form a deflecting element for the stock, that is, their outline in plan view taken with the exit or outlet from the beater roll appears cowl-like. Such a deflector (and I may use one or both of them) being closed at one end, directs the stuff in one direction only and by their main walls at an acute angle to the beater roll delivery, the stuff delivered from the roll backs up against the deflecting partitions where, due to their

angularity, it is wedged or urged along, all the while adding its weight and pressure to 35 the stuff in the channel to accelerate its movement.

Having now particularly described and ascertained the nature of my said invention and in what manner the same is to be performed, I declare that what I claim is—

1. In combination in a beating engine, a beater roll for beating and elevating the stuff, a single substantially spiral, continuous, channel having a uniform gradient for 45 conveying, with a minimum of friction, the stuff from adjacent the top of the roll to a point adjacent the bottom of the roll, and deflecting means for diverting the stuff from the top of the roll into said channel and 50 accelerating the flow thereof through said channel in order to pass the stuff through the channel eddylessly, whereby the stuff may be worked while in less fluid condition than heretofore. 55

2. The apparatus of claim 1, in which the deflecting means is curved in a direction transverse to the direction of stuff flow as it comes from the roll.

In testimony whereof I have signed my 60 name to this specification in the presence of two subscribing witnesses.

WILHELM RABUS.
